BOWLING SCORE SHEET DISPLAY TABLE

Royal J. MacMillan, St. Paul, Minn., assignor of
one-third to Franklyn M. Lewis and one-third
to William C. Kregel, both of St. Paul, Minn.

Application September 2, 1941, Serial No. 409,177

3 Claims. (Cl. 282—15)

My invention relates to the combination of a bowling score sheet display table which includes a supply compartment for the scoring sheets and a storage compartment for carbon copies of the score sheets.

A feature resides in providing a compartment for holding a series of score sheets which are connected together to provide a continuous supply of score sheets, together with duplicate score sheets associated with the original score sheets, so that when a score is recorded on the original sheet, a duplicate is made. The cabinet or table device has means for storing the duplicate score sheets and thus provides means for keeping a record for the bowling alley at all times. Heretofore in bowling alleys the score sheet has been kept by the bowling alley so that the bowler does not have an official copy of the score which he has made. With my combination the table or cabinet for displaying the same, makes it possible for the bowler to receive the original score sheet, whereas, the bowling alley retains the duplicate score sheet for its record.

It is also a feature to provide a display table which has a compartment for a supply of score sheets which may be maintained in flat overlapped or rolled relation, the duplicate sheets being associated with the original sheets.

By this means of keeping the score sheets, the pin setters as well as the alley operator and other employees, are protected by the duplicate score sheet so that an absolute count of all games rolled on any given alley is maintained.

This way of providing a table means for displaying the score sheet is very desirable.

A further feature resides in providing a table or cabinet wherein a storage compartment is provided for the carbon copies or duplicate score sheets. This storage compartment may be kept locked by the bowling alley operator if desired. My table is also provided with a storage compartment for a supply of carbon tissue and means for holding a portion of the carbon tissue extended between the original and duplicate score sheet so as to make a true and accurate carbon copy of each score sheet. The display table is provided with means for drawing the score sheets into operating position and into the storage compartment for the duplicate score sheets.

These features together with other details and objects will be more fully and clearly hereinafter set forth.

In the drawings forming a part of this specification:

Figure 1 is a perspective view of my table used

in carrying out my method of issuing and keeping a copy of bowling score sheets.

Figure 2 is a vertical section through the empty table and a portion of the standard being broken away.

Figure 3 is a plan view of my bowling score sheet table showing some of the parts in dotted position, and with the score sheet removed therefrom.

10 Figure 4 is a rear view of the top of my bowling score sheet table.

Figure 5 illustrates a portion of my continuous bowling score sheet in plan view.

15 Figure 6 is a section similar to Figure 2, showing the operation of my score sheet as it is extended through the machine and showing the score sheet in operative position on top of the table.

Figure 7 is a plan view looking down on the 20 table shown in Figure 6, with my score sheet in operative position.

Figure 8 is a section on the line 8—9 of Figure 7, showing the storage compartment for the carbon tissue.

25 Figure 9 is a longitudinal section on the line 9—9 of Figure 7, of the tissue storage compartment.

Figure 10 is a sectional detail on the line 10—10 of Figure 7, of a portion of the table and score sheet, showing the carbon tissue extending between the original and duplicate score sheets.

Figure 11 is a sectional detail longitudinally through my duplicate score sheet, showing the stitching of the sheet at the line of perforation and a portion of the sheets being broken away.

35 Figure 12 is a section similar to Figure 6 of an alternative form of my bowling score sheet table.

40 My combination consists of a series of bowling score sheets 10 connected together in an endless form with the table A for displaying the same and supporting the sheets so that the bowler or operator may readily mark up his score, and provides a desirable means of issuing a score sheet 10 to the bowler. The table A may be mounted upon a standard 11 and supported by the base 12 or may be supported in any suitable manner and if desired may be attached to the wall in the bowling alley.

45 The table A is formed with an upper writing surface 13 across which the bowling score sheets 10 are stretched. A storage compartment 14 is formed in the table for the supply of bowling score sheets and the supply of score sheets 10 may be supported in a flat pack B, as illustrated.

in Figure 6, in the compartment 14, or the supply of score sheets in the roll C may be supported in said compartment ready for use.

The score sheets 10 are joined together along the perforated line 15 so that they may be separated from each other and directly beneath the score sheet 10 is a duplicate score sheet 10'. One end of the pack B or roll C is passed through the slot 16 in the table top 13 and over the same and down through the slot 17 to the storage roll 18. The roll 18 is operated by the knob or handle 19 to draw the score sheets 10 into proper position on the writing surface 13 of the table A. In feeding the sheets 10 and 10' over the writing surface 13 from the opening 16, the sheets are divided by the channel guide member 20 in which the marginal edge of the carbon tissue 21 slides.

The carbon tissue 21 comes from a supply roll 22 positioned in the recess 23 of the table top 13 and closed by the cover 24. The carbon tissue 21 is threaded between the original score sheet 10 and the duplicate 10' with the tissue extending transversely across the table A and between the sheets 10 and 10' so as to make a duplicate copy on the sheet 10' when the original score sheet 10 is written upon. Thus a bowling score is simultaneously marked up on both the original and duplicate. The free end of the carbon tissue is held by the bar 25 which frictionally engages the end of the carbon tissue 21. When it is desired to renew the carbon tissue, it is only necessary to loosen the bar 25 which is pivoted at 26 and hooked under the pin 27 on the free end to permit the bar 25 to swing out as illustrated in Figure 3. This operation also assists in threaded the free end of the carbon tissue 21 under the bar 25.

The score sheets 10 and 10' are threaded under the bar 30, one end of which is pivoted at 31 and the other end of which is hooked under the pin 32 so that the bar 30 may be moved as illustrated in dotted outline in Figure 3 to permit the score sheets to be more easily threaded under the same. The bar 30 also forms a straight edge against which the perforated edge 15 of the score sheet 10 may engage so that the original score sheet 10 may be torn off while the duplicate sheet 10' passes on through the opening 17 into the storage compartment 28 provided for the roll 18 in the table A. Thus as the bowler completes his score sheet the knob 19 may be operated to draw the duplicate score sheet 10' into the storage compartment 28 while the original score sheet is taken by the bowler. The storage compartment 28 may be closed by the door 29 and if desired this door 29 may be locked to insure the safe keeping of the duplicate score sheets 10' on the roll 18 for the operator or proprietor of the bowling alley.

Where the supply of score sheets is kept in a roll C, as illustrated in Figure 12, a friction roller 33 may be provided to take the place of the bar 30 and which roller is adapted to be operated by the belt 34 from the shaft 35 which supports the roll 18, thus providing a pulling roller 33 against the score sheets 10 and 10' to assist in drawing the same over the top 13 of the table A to facilitate the operation of the movement of the score sheets into the desired position.

Each original score sheet 10 is provided with a serial number 36 or other identification indicia, and the duplicate sheet 10' corresponding to the original sheet 10 carries the same identification serial number 36, so that the original and duplicate correspond and may be identified with

each other, namely, one as the original and the other as a carbon copy of the original. Each score sheet 10 and its duplicate have the same serial identification and the consecutive sheets 5 have different serial identification means so that as the score sheets are used up the identification serial 36 will change on each original and duplicate sheet to prevent any errors and to make the carbon copies authentic and readily identifiable with the originals.

The perforations 15 act to stitch the sheets 10 and 10' together so that they will follow through the slot 16 in uniform coinciding position to insure registry of the duplicate sheet 10' with the original sheet 10. It is desirable to form the bowling sheets 10 with spaces 37 positioned around the score sheet proper, which may be used for any suitable purpose, such as advertising or other display indicia which it is desirable to associate with the score sheet 10. Where advertising is used surrounding the score sheet 10 it may be placed in an attractive manner and has the advantage of not only decorating the score sheet, but increases the value of the advertising by reason of the fact that the bowler will display his score sheet to his friends and family and thus a large number of people will view the advertising or indicia in the spaces 37.

In accordance with the patent statutes I have described the principles of operation of my invention and while I have illustrated a particular form of table and support for the bowling sheets, the same is only illustrative, and it is apparent that other means may be provided for supporting and displaying the same to carry out my method within the scope of the following claims.

I claim:

1. A bowling score sheet display table including a storage compartment for a supply of original and duplicate score sheets, a separate storage compartment for the duplicate score sheets after they have been used, means for moving the sheets into operative position across the top of said table, a separate elongated storage compartment for a supply of carbon tissue, a channel guide member extending transversely across said table, a pair of flat bars pivoted to the top of said table, one of said bars providing a means for holding the carbon tissue between the score sheets in operative position, the other of said bars having a rule edge against which the original score sheets may be torn off, said channel guide member adapted to protect the edge of the carbon tissue which extends between the score sheets, and means for carrying the carbon copy of the score sheet into said separate storage compartment therefor.

2. A table for bowling score sheets comprising a storage compartment, an elongated slot in the top of said table leading into said storage compartment, a second storage compartment adjacent said first-named storage compartment, a second elongated slot in the top of said table leading into said second-named storage compartment, a hinged door for opening or closing said second-named storage compartment, an elongated storage compartment formed in the top of said table, a flat plate-like cover for closing said elongated storage compartment, a pair of flat bars pivoted to the top of said table, said bars adapted to lie in a plane at right angles to each other, and a channel guide member extending transversely across the top of said table.

3. A bowling score sheet displaying table comprising a storage compartment for a supply of

original and duplicate score sheets, a second storage compartment adjacent said first-named storage compartment for the duplicate score sheets after they have been used, a roller in said second-named storage compartment upon which the duplicate score sheets are wound, said roller providing a means for moving the main score sheets and the duplicate score sheets across the top of said table, an elongated compartment in the top of said table for a supply of carbon paper, a flat plate-like top for closing said elongated compartment, said flat plate having bearing means for the roll of carbon paper, channel guide

5
10

means extending transversely across said table, said channel providing a protecting means for the edge of the carbon paper which is adapted to lie transversely across the table top between the main and duplicate score sheets, a pair of flat bars pivoted to the top of said table, one of said bars having a rule edge against which the original score sheet may be torn off, the other of said bars providing a means for holding the carbon tissue extending between the main score sheets and the duplicate score sheets in operative position.

ROYAL J. MACMILLAN.
